UNITED STATES PATENT OFFICE.

CHARLES A. HOMANS, OF WINCHESTER, MASSACHUSETTS, ASSIGNOR, BY DIRECT AND MESNE ASSIGNMENTS, TO LYDIA K. HOMANS, OF SAME PLACE, OSCAR F. GUNZ, OF RUTHERFORD, NEW JERSEY, AND ISIDORE L. BAEZA, OF NEW YORK, N. Y.

ELECTRIC LAMP.

SPECIFICATION forming part of Letters Patent No. 367,002, dated July 19, 1887.

Application filed July 19, 1886. Serial No. 203,378. (No model.)

To all whom it may concern:

Be it known that I, CHARLES A. HOMANS, of Winchester, in the county of Middlesex and State of Massachusetts, have invented certain new and useful Improvements in Electric Lamps, of which the following is a specification.

This invention relates to certain new and useful improvements in that class of electric lamps in which two carbon electrodes are used, and in which the light-arc is formed in a gas that does not affect the carbons injuriously.

The object of my invention is to facilitate the detaching of those parts of the lamp in which the upper-carbon holder and the helix for governing the upper carbon are held, and also to facilitate removing and adjusting the lower carbon and cleaning the lamp.

20 A further object of my invention is to simplify the construction of the lamp.

The invention consists in the construction and combination of parts and details, as will be fully described and set forth hereinafter.

25 In the accompanying drawings, Figure 1 is a cross-sectional view of the upper part of the lamp. Fig. 2 is a sectional detail view of the lower part of the helix and the upper-carbon holder. Fig. 3 is a cross-sectional view of the 30 lower part of the lamp.

Similar letters of reference indicate corresponding parts.

The lamp-globe A is provided at its top with an external screw-threaded neck, B, on which 35 a ring, C, is screwed, provided on its upper end with an exterior flange, D. A suitable packing—such as red-lead, whiting, rubber, cement, or other like material—is spread on the thread before screwing on the said ring.

40 A packing-ring, E, is placed on the flange D, and on said ring E the lower annular exterior flange, F, of a circular cap, G, is placed, and bolts H, provided with nuts, are passed through apertures in the flanges D F and the packing-ring E, and the nuts drawn up tight for the purpose of forming a tight joint. In place of bolts and nuts, ordinary screws or like fastening devices may be used for holding the flanges

and packing-ring together. On the middle of the top of the cap G a cylinder, J, is formed, 50 which is of less diameter than the said cap, as shown, which cylinder is provided at the upper end with an outwardly-projecting annular flange, K, on which a packing-ring, K', is placed, and on which packing-ring the exterior annular flange, L', of the cap L is placed, and bolts L², provided with nuts, are passed through the flanges L' L and the packing-ring K'. The cap L is open at the bottom and closed at the top. In the upper part of the cylinder 60 J a cross-piece, M, is fastened, from which a tube, O, is suspended by means of a ball-and-socket joint, O'. A wire is coiled around the tube, O, forming the helix P, one end of the wire of the helix being connected with the 65 binding-post Q, fastened in an insulating-piece, Q', in the side of the cylinder J, and on the said binding-post Q the positive line-wire a is held by a screw of the usual construction. The other end of the wire, forming the helix, 70 is connected by the wire b with the upper-carbon clamp R, provided with the binding-screw R', which carbon-clamp R is fastened at the lower end to the carbon-holder rod S, passed through the tube O. A spring-tongue, T, is 75 fastened on a plate on the bottom of the helix P, and its free end rests against the carbon-holder rod S.

A pin, U, projects from the carbon-holder rod S a distance from the top of the carbon-clamp R greater than the length of the spring-tongue T, for a purpose that will be set forth hereinafter. The helix P is surrounded by a metal covering, P', against which the inner ends of three screws, V, rest, which are screwed 85 through projections V', formed on the inner surface of the cylinder J, near the lower end of the same.

The bail I for hanging the lamp is provided at its top with an eye, I', and is passed through 90 apertures in the ends of the cross-piece W, resting on the top of the cap L, and through an exterior flange, W', formed along the top edge of the cap G. Hooks c are formed on the lower ends of the shanks of the bail I, and 95 are passed through loops d, fastened on the

flange F along the bottom edge of the cap G. Nuts e are screwed on the shanks of the bail I, directly above the cross-piece W, and a binding-screw, f, is screwed through the cross- 5 piece W, at the middle of the same, and into the cap L, for the purpose of holding and binding the cross-piece W on the top of the cap L.

The globe A is provided in its bottom with an aperture, f'. On the inner surface of the 10 bottom of the lamp, at the said aperture f', a cushion, g, of cork covered with asbestos, is placed, and on said cushion g a metal disk, h, is placed, which is provided with a recess, i, for receiving the rounded bottom button, j, 15 formed on the lower end of the carbon-holder k, which is provided with a binding-screw or any other suitable device for holding the lower carbon. On the under side of the lamp-globe a cushion, l, made of cork and covered with 20 asbestos, is placed, which ring is provided at its middle with a neck fitting into the aperture f'. A brass disk, m, having a central screw-threaded aperture and provided with a screw-thread on its rim, is placed against the 25 asbestos-covered cushion l, and a heavy soft-rubber packing-ring, n, is rested against the brass disk m. A metal disk, o, having a screw-threaded aperture, is placed against the bottom of the rubber cushion n, and has a 30 smooth outer rim. The rod p, having a screw-thread formed on its upper part, is screwed through the threaded aperture of the disk o, passed through the rubber cushion n, screwed through the disk m, passed through the aperture 35 in the asbestos-covered cushion g, and its upper end is screwed into the rounded bottom of the button of the lower-carbon holder. A cylindrical casing, r, having its upper part threaded internally, is screwed on the outside 40 of the disk m, and surrounds the packing n and the disk o. The conducting-wire s for the lower carbon is held by a binding-screw, t, on the lower end of the rod p. Two or more screws, U, are screwed through internal projections of the casing r, and at their free ends 45 rest against the rod p.

By holding the lower carbon holder k and turning the rod p the cushion l is pressed against the bottom of the globe, and the button j on the lower-carbon holder is drawn downward, and as it exerts a pressure on the plate h the cork disk g between said plate and the inner surface of the button is pressed downward against the inner surface of the bottom of the globe, whereby an absolutely tight joint is formed. By turning the disk o, by means of a suitable implement, it is moved up toward the disk m, whereby the rubber packing n between the disks o and m is compressed 55 and bulged outward, so that its outer edges press against the sides of the cylindrical casing, thereby forming a tight joint.

The lower carbon can be adjusted to have any desired inclination by means of the screws 60 U'. The screws U' on the one side are loosened and the screws U' on the other side turned up, and acting on the rod P press it in the di-

rection in which the screw that is drawn up moves. The button j forms the fulcrum on which the rod p moves, and the carbon is removed in the inverse direction of the rod. As the button j is rounded, it fits in the recess formed in the plate h. When it is desired to clean the lamp, the wire a is disconnected, the bolts H removed, and the cap G unscrewed, 70 and the rod O and the helix P are all removed from the globe. The neck B of the globe is of sufficient width to permit the inserting of the hand and a cloth, rag, or wiper to permit the cleaning of the inside of the globe. 75

The upper-carbon holder can be adjusted by means of the screws V. As the rod S moves up and down in the tube O, the end of the spring T slides on the surface of the rod and keeps the said surface clear and bright, thereby 80 preventing oxidation, which is absolutely necessary for preventing the sparking of the lamp. The pin U is provided at such a distance from the bottom of the rod S that the said pin strikes the bottom of the helix and prevents the same 85 from moving higher in the tube O. Otherwise it might happen that the spring-tongue T would snap over the top plate of the clamp and hold the upper carbon raised and prevent it from descending. 90

I am aware that it is not new to connect the line-wire direct with the wire of the helix, or the wire of the helix direct with the upper-carbon holder. I am also aware that it is not new to adjust the inclination of the upper and lower carbons by means of screws the ends of 95 which act on the carbon-holders, and I do not claim these constructions, broadly.

Having thus described my invention, I claim as new and desire to secure by Letters Patent— 105

1. In an electric lamp, the combination, with a globe having a neck, of a cap on said neck, on which cap a cylinder is formed, a cross-piece in the cylinder, a tube jointed to and suspended from the cross-piece, and a helix 110 formed on the said tube, substantially as herein shown and described.

2. In an electric lamp, the combination of a globe having a neck, a ring held on said neck, a cap on the ring, from the top of which 115 a cylinder projects, a cross-piece on the top of the cylinder, a tube jointed to and suspended from the cross-piece, a helix formed on the said tube, adjusting-screws passed through the sides of the cylinder and resting against the 120 outer surface of the helix, substantially as shown and described.

3. In an electric lamp, the combination, with a helix, of a carbon-holding rod passed through the bore of the helix and a spring-tongue 125 fastened on the helix and resting freely against said carbon-holding rod, substantially as shown and described.

4. In an electric lamp, the combination, with the helix, of a carbon-holding rod passing freely through the bore of the helix, a spring-tongue fastened to the lower end of the helix and having its free end resting against said carbon-holding rod, and a pin projecting 130

- from the carbon-holding rod a distance from the lower end of the same slightly greater than the length of the spring-tongue, substantially as shown and described.
- 5 5. In an electric lamp, the combination, with a helix, of the carbon-holding rod passed through the bore of the helix and a scraper resting against the holding-rod and fixed to the lower end of the helix, substantially as shown and described.
- 10 6. In an electric lamp, the combination, with a globe having a bottom aperture, of cork cushions resting on the inner and outer surfaces of said globe at said aperture, a carbon-holder provided with a rounded button, a disk placed on the upper surface of the inner cushion, on which disk the rounded button rests, and a screw-rod screwed into said rounded button or head, substantially as set forth.
- 15 7. In an electric lamp, the combination, with a globe having a bottom aperture, of cork cushions resting on the inner and outer surfaces of the globe at said aperture, a carbon-holder resting on a plate or disk on the inner cushion, a disk below the outer cushion, and a screw passed through the said several disks and cushions and passed into the carbon-holder, substantially as shown and described.
- 20 8. In an electric lamp, the combination, with the globe, of the cushions *g l* on the inside and outside of the globe, the disk *h*, resting on the inner cushion, *g*, the disk *m*, resting against the bottom of the lower cushion, which disk has its outer edge screw-threaded, the cylindrical casing *r*, screwed on the disk *m*, the rubber packing *n*, resting against the disk *m*, the disk *o* below the same, the carbon-holder *k*, and the rod *p*, having its upper screw-threaded end screwed through the screw-threaded apertures of the disks *o* and *m*, the upper end of the rod *p* being screwed into the bottom of the carbon-holder *k*, substantially as shown and described.
- 25 In testimony that I claim the foregoing as my invention I have signed my name in presence of two subscribing witnesses.
